UNITED STATES PATENT OFFICE.

PAUL F. DEGENKOLB, OF ITASCA, ILLINOIS.

POLISHING DEVICE.

1,404,839.

Specification of Letters Patent. Patented Jan. 31, 1922.

Application filed November 26, 1920. Serial No. 426,411.

To all whom it may concern:

Be it known that I, PAUL F. DEGENKOLB, a citizen of the United States, residing at Itasca, in the county of Du Page and State 5 of Illinois, have invented certain new and useful Improvements in Polishing Devices, of which the following is a specification.

This invention relates to a device in which is combined a reel and a cleaning and polishing cloth adapted to be wound thereon, both being retained within a casing of convenient and compact size. A device of this character may advantageously be carried around in the pocket, in a valise, or otherwise, to be 10 used for such purposes as cleaning and polishing shoes or the like.

As an object of this invention, I have sought to devise a structure which is simple and certain in its operation, a device wherein 20 the cloth will be automatically rolled up when not in use, and wherein one cloth may be readily substituted for another, and a device wherein the parts are so arranged that wherever necessary the casing may be opened 25 up without loss of the operating parts therein. These and other objects will more clearly hereinafter appear from the specification and claims, and from the accompanying drawing wherein an exemplification of 30 this invention is shown in the manner following:

Figure 1 is an elevation of the casing with the cloth rolled up therein;

Fig. 2 is an enlarged longitudinal section, 35 the central portion being broken away; and

Figs. 3 and 4 are transverse sections taken, respectively, on lines 3—3 and 4—4, of Fig. 1.

The device of my invention, as shown in 40 the drawing, comprises a tubular casing A having one end closed by a wall 5, a flanged cap B being fitted upon its other end. If desired, the walls of the casing adjacent its open end may be outwardly crimped to form 45 a shoulder 6 by which inward movements of the cap are stopped. Means are preferably provided for preventing rotation of the cap upon the casing, and this may take the form of a button 7 formed exteriorly of the casing 50 adjacent its end and adapted to lie within a slot 8 formed by bulging the flanged walls of the cap, as shown best in Fig. 1.

Within the casing is a reel C which is 55 removably mounted in place. For this purpose I employ two studs 10 one adapted for insertion through a central opening 11 in the

casing wall 5, and the other through a similar opening 12 in the cap, each stud being threaded to connect with the proximate end of the reel. Upon each stud I further provide a head 13 in which is swingingly mounted a bow 14 serving the double purpose of facilitating rotation of the stud, and of an eye through which a cord or hook may be passed for supporting the device. Each 60 stud being similar, it may be unscrewed from the reel so that the latter may be withdrawn from the casing when the cap is removed therefrom. Normally only the stud passing through the casing end 5 need be unscrewed 65 for this purpose, as the reel, together with the cap, would then be free to disengage from the casing. It follows also that when both studs are connected with the reel, the cap is thereby made fast to the casing. The 70 mounting of each stud within the end wall 5 or the cap is sufficiently loose to permit free rotation of the reel within the casing.

Arranged to wind upon the reel is a cloth D of a kind which is suitable for cleaning 80 and polishing purposes. Each end of the cloth is suitably hemmed to provide a loop that in the one instance connects with the reel, and in the other with a stick E that lies exteriorly of the casing which is provided 85 with a slit 20 to permit the cloth to pass therethrough for this purpose. To co-operate with the hemmed ends of the cloth the reel and stick are each provided with a slot 21 extending longitudinally through its body 90 in the middle region for a distance slightly in excess of the width of the cloth; and near the middle of the slot is a lateral opening 22 to permit inspection of the cloth hem preliminary to spreading the cloth lengthwise 95 of the slot. By a construction such as this, each end of the cloth may be readily attached or detached relatively to the reel or stick, as the case may be, but under normal operating conditions will tend to remain 100 connected in place.

Near the end of the reel which lies adjacent the cap is a head 25 in the form of a flange which just fits into the open end of the casing. Between this flange and the cap 105 is an annular space wherein I have arranged a coiled spring 26 whose inner end is made fast to the reel as by means of a pin 27, the outer end being fastened to the cap as at 28. The tendency of this spring is to wind 110 up the cloth upon the reel so as to normally hold the stick E adjacent the casing. When-

ever the cloth is required for use, the stick may be grasped to unwind the cloth against the tension of the spring, so that, by holding the stick in one hand and the casing in the other, any desired length of cloth is available for cleaning or polishing purposes. The requisite degree of tension may be obtained by disconnecting the stud 10 at the casing end 5, and then sliding off the cap to the required distance to disengage the button 7 from the slot 8 following which the cap may be rotated sufficiently to wind up the spring as desired. It will be understood, of course, that one or more slots 8 may be provided, so that the cap may be adjusted upon the casing in any one of several positions.

The device that I have described is exceedingly simple in its manufacture and assembly, as well as in its operation. It permits of all the parts being retained within a compact casing which protects articles surrounding the same from the soil or dirt which may have accumulated upon the cloth through use. Fresh cloths may be substituted at any time by merely removing one of the studs and taking out the reel following which the ends of the cloth are disengaged therefrom, as well as from the stick, a new cloth being thereafter substituted in its place.

I claim:

1. In a device of the kind described, the combination of a tubular casing closed at one end, a cap adapted to close the other end 35 of the casing, a reel within the casing, a stud entered through the casing end and another stud through the cap, each removably connected with the proximate end of the reel to provide a mounting therefor, a flange 40 upon the reel near the end which is adjacent the cap providing between itself and the cap an annular space, a spring coiled within said space having one end secured to the reel and the other to the cap, means for preventing relative rotation between the cap and casing, a cloth having one end secured to the reel and adapted to be wound thereupon, there being a slit through the casing through 50 which the cloth may pass, and a stick secured to the opposite end of the cloth and arranged exteriorly of the casing, substantially as described.

2. In a device of the kind described, the combination with a casing within which is mounted a spring reel, of a cloth having one end looped to connect with the reel, there being formed in the latter a longitudinal slot extending through its body and a lateral opening into the slot through which 55 the cloth loop may pass preliminary to being spread lengthwise of the slot, there be-

ing a slit in the casing through which the cloth may pass to the outside thereof, substantially as described.

3. In a device of the kind described, the combination with a tubular casing having a wall at one end thereof and a cap removably secured to its other end, of a spring reel mounted within the casing having one of its ends journaled in the cap and its other end in the end wall of the casing, means connecting the cap to the reel, means for normally preventing disengagement of the reel from the casing end, but adapted also to permit such disengagement whereby the reel, together with the cap, may be removed as a unit from the casing, and a cloth having one end secured to the reel and adapted to be wound thereupon, the casing being provided with a slit through which the cloth may pass to its exterior, substantially as described.

4. In a device of the kind described, the combination with a casing on which is removably fitted a cap, of a spring reel having one end journaled in the cap and the other end in the opposite wall of the casing, the reel being removably journaled in the casing wall whereby the cap, together with the reel, may be withdrawn from the casing, and means for adjusting the cap non-rotatably to the casing in a desired rotative position, substantially as described.

5. In a device of the kind described, the combination with a tubular casing closed at each end and a spring reel arranged within the casing, of a mounting for the reel comprising two threaded studs, one secured by a threaded connection to each end of the reel, and each inserted through the proximate 100 end of the casing, in which it is free to revolve, each stud being formed with a head which lies exteriorly of the casing, and having in its head a swinging bow by which the stud may be rotated to effect its connection 105 with the reel, substantially as described.

6. In a device of the kind described, the combination of a tubular casing closed at one end, a cap removably secured to the other casing end, a reel mounted within the casing and connected for removal with the cap, spring means within the cap for rotating the reel, and a mounting for the spring means within the cap such as to permit of a complete withdrawal of the reel from the 110 casing, together with the cap, without disassembling of the parts associated therewith, substantially as described.

PAUL F. DEGENKOLB.
